UNITED STATES PATENT OFFICE.

ALBERT E. STEIN, OF LOS ANGELES, CALIFORNIA.

BOX FOR EGGS AND THE LIKE.

1,003,013.

specification of Letters Patent. Patented Sept. 12, 1911.

Application filed July 8, 1910. Serial No. 571,098.

To all whom it may concern:

Be it known that I, ALBERT E. STEIN, a citizen of the United States, residing at Los Angeles, in the county of Los Angeles and State of California, have invented new and useful Improvements in Boxes for Eggs and the Like, of which the following is a specification.

This invention relates to a paper box for 10 eggs or similar articles, and it consists primarily in the provision of a box which is easily and inexpensively manufactured from a single piece of paper or card-board, which may be handled in large numbers in a flat 15 state before being filled with the commodity intended to be carried, and which will form a stiff and indestructible package when set up for use.

There are minor features which will be 20 come apparent in the following specification.

The box as now made consists of a single piece of card-board cut to the required shape and partially fastened together so 25 that the remaining operations of assembling the box are merely those of placing the different parts in correct relation, requiring no materials except those which are supplied and no pasting or gluing operations. The 30 box is made with an interior horizontal partition supported at a certain distance from the bottom by being secured to both side walls of the box and by being supported down the center.

35 It will be understood that I lay no claim to the formation of the box from a single piece of material, to the provision of the horizontal position or to the broad provision of center supports for the partition; but I 40 do wish to claim the construction and mounting of the horizontal partition on the front and rear walls of the box and the peculiar construction of my central partition support. The construction of the partition 45 includes the peculiar cutting of apertures and flaps for holding the eggs or other articles securely in position without danger of breaking by movement.

There are also other features of the general construction of the box which I claim 50 as new. These features have to do with the formation of a simple and effective closure of the box and the stiffness of the whole structure when closed. Prime among these 55 is the peculiar construction of the front

member of the box and of the flap on the end wall, this combination affording a simple and effective lock, and, in combination with the partition features, holding the box in shape while being filled when the top 60 is up. These features, and accompanying ones will appear at greater length in the following specification.

In the accompanying drawings: Figure 1 is a plan view of the blank for the 65 box, the full lines representing the cut edges of the different portions of the blank and the dotted lines representing the scoring or creasing lines at which the blank is to be folded. Fig. 2 is a view showing the 70 first stage in folding the box. Fig. 3 shows the box collapsed for shipment. Fig. 4 is a section showing the position of the wire stitching. Fig. 5 is a perspective view showing the first step in setting up the box. 75 Fig. 6 is a similar view showing the second step. Fig. 7 is a similar view showing the box ready for closure. Fig. 8 is an enlarged detail perspective showing the means for locking the end walls in place. Fig. 9 is a 80 detail perspective showing the construction of the horizontal partition in the box and showing the form and position of the flaps for holding the eggs in place to prevent them from having either a vertical or horizontal movement. 85

In the drawings a blank is shown which consists of the following portions; a top cover 5 having a flap 6, end covers 7 having flaps 8, back wall 9, end pieces 10 attached thereto, bottom 11, ends 12 attached thereto, end flaps 13, front 14, front partition supporting portion 15, horizontal partition 16, rear partition supporting flap 17, and end partition support and flaps 18 and 19. 95 The peculiar cutting of partition 16 will be explained hereinafter.

The first operation consists in applying adhesive material to flap 17 and in bending the blank over on line 20 between portions 14 and 15, laying partition 16 on portions 11 and 14 as shown in Fig. 2. The other end of the blank is then bent over on line 22 between portions 11 and 9. Portion 9 is thus forced into contact with the adhesive 100 material on flap 17 and the flap and portion 9 are secured together. Portion 5 is then bent back on line 50 to the position shown in Fig. 4 and staples 21 or other stitching is applied to hold portions 14 105 110

and 15 together as illustrated. The box is sold to the trade, and otherwise handled before filling, in the form shown in Fig. 3. When it is desired to use the box it is opened up as shown in Fig. 4 by pulling upwardly and rearwardly on portions 5 and 6 in the direction indicated by the arrow in Fig. 4, bending along line 23 at the edge of flap 7 and along line 24 at the edge of partition supporting portion 15. The sizes of the various portions are so arranged that when the box is opened up the front edge of partition 16 will be supported at the same height on the front wall 14 as the rear edge of the partition is supported on rear wall 9. The next operation comprises the turning down of supporting members 18 and the passage of flaps 19 within and behind front 14. End pieces 10 are then turned in as shown in Fig. 5. Ends 12 are then turned up and end flaps 13 forced into the space between flaps 19 and portion 15 and front 14. The upper edges of flaps 13 are formed with straight portions 25 which must be forced into the space noted and which prevent the withdrawal of ends 12 unless some considerable force is applied thereto. Upon closing the box flap 6 is slipped inside front 14, end covers 7 are folded over ends 12 and flaps 8 are slipped into spaces 26 between flaps 13 and front 14.

The simplicity of assembly of my box is one of its salient features. The peculiar construction allows of this simplicity and 35 also provides the necessary strength and stiffness. It is noted that the ends 12 are only locked to the front edge of the box instead of being locked to both front and rear. It is usually necessary to lock the 40 ends to both front and rear in order to hold both front and rear walls in proper position; and this operation is often awkward to perform and disastrous to the shape of the box. In my box the rear wall is 45 supported by being attached to the partition 16; hence it is unnecessary to lock the end walls to the rear, the simple locking of the front wall amply sufficing to hold the front and, through the connecting partition, the rear wall in vertical positions. 50 When the top is closed down additional support and stiffening members are made available, the top 5 connecting the upper edges of the front and rear walls and the end 55 covers 7 reinforcing ends 12. The box will remain closed tightly and securely without the necessity of tying or sealing in any manner, the different flaps and covers all tending to hold each other in place.

60 It will be seen that the cover cannot be lifted unless flaps 8 are removed from their positions by lifting end covers 7. Any ordinary pull at the top will not suffice to open the box and expose the contents. This 65 system of interlocking flaps and duplicate

covers also lends rigidity to the complete box, giving it sufficient strength to protect the inclosed commodity.

Partition 16 is cut into the peculiar formation shown in Fig. 1. The partition 70 is divided into a number of squares, in each of which the card-board is cut into three flaps. A center stationary strip 30 separates the cut squares and extends from end to end of the partition, while a number of transverse stationary strips 31 extend across the partition, the transverse and longitudinal strips inclosing the squares in which the cuttings are made. There are two styles of cuttings, the squares on one side of the longitudinal strips being cut in one manner while the squares on the other side of the longitudinal strips are cut in a slightly different manner. The material within each of the squares is cut into three pieces, each piece 80 having an edge left in connection with one of the strips 30 or 31 so that it is not entirely detached from the body of the partition. Flaps 35 and 35^a are left attached to opposite edges of strip 30. These flaps are provided with extensions 36 and 36^a which are adapted to cross each other as shown in Fig. 8, when the two flaps are thrown down beneath the partition. When crossed, the ends just touch bottom 11 of the box. 90 The engaging edge of flap 35 is made square to the line of attachment of the flap to strip 30 while the corresponding edge on flap 35^a is laid off diagonally so that the diagonal edge will hook over the square edge as shown in Fig. 8 and so that the operation of hooking the edges together may be accomplished by passing extension 36 through opening 37 rather than by forcing the two extensions by each other. In this 100 manner the flaps and their extensions are not bent or broken by being placed in position. These flaps do not directly form a part of the egg supporting device. They prevent the egg from moving laterally toward the center of 105 the box but they do not support the egg as do the other two flaps. They are primarily for the purpose of supporting the central portion of the partition and preventing that portion of the partition from being forced 110 down when the eggs are placed in the box. This is one of the main features of my invention; the provision of a support which does not depend upon the egg to force it into position to support the central portion 115 of the partition. The other two flaps of the squares 40 and 41 on one side and 40^a and 41^a on the other side of central strip 30, are cut in the configuration shown and utilize the remaining portions of the squares 120 without waste. These portions are attached to transverse strips 31 and are adapted to be folded downwardly as shown in Fig. 8. In this figure it will be seen that edges 42 and 43 bear against the wall of the box and 125 130

thus form bracket braces to prevent strips 31 from bending down or breaking when the eggs are placed in the box. This bracing feature is another of the prime points of my invention.

5 An egg is placed in each of the cut squares, pushing flaps 40 and 41 down to the position shown. The height of partition 16 above the bottom of the box is so arranged that the center of the egg passes below the 10 points of engagement with flaps 40 and 41. These flaps then act in the manner of valve flaps and prevent the withdrawal of the egg until they are pushed aside. In fact, the 15 box may be turned upside down when filled with eggs without dropping any of the 20 eggs out of place. The eggs each touch the box structure and are held in place laterally at three points, two points where the egg is engaged by flaps 40 and 41 and a third point where the egg touches central strip 30. This method allows for different sized eggs 25 without the necessity of making different sized boxes, the flaps 40 and 41 merely being moved farther down when a larger egg is placed in the box.

From the foregoing it will be seen that my invention consists mainly in the features which provide a strong and durable box, 30 easily set up, and a box which will hold its shape and support the eggs securely even when little or no attention is given by the

person who places the eggs in the box. The support and braces for the egg supporting partition makes it impossible to 35 injure the partition unless an exceptional force is applied thereto. The stapling and gluing of the box provide for easy and accurate assembly without any danger of bending or breaking the egg supporting parti- 40 tion.

Having described my invention, I claim:

1. In a box of the character described, a partition having a central stationary strip therein, flaps hinged to both edges of the 45 strip and adapted to be turned into engagement with each other, and interlocking means on the flaps.

2. In a box of the character described, a partition comprising longitudinal and trans- 50 verse stationary strips, flaps hingeably secured to the opposite edges of the strips, the flaps on the opposite edges of the longitudi- nal strips being adapted to be turned into engagement with each other and having in- 55 terlocking means thereon.

In witness that I claim the foregoing I have hereunto subscribed my name this 1st day of July 1910.

ALBERT E. STEIN.
